UNITED STATES PATENT OFFICE.

ABRAHAM MILLER, OF NEWARK, ASSIGNOR TO THE NEWARK MACHINE COMPANY, OF COLUMBUS, OHIO.

CLOVER-HULLER.

SPECIFICATION forming part of Letters Patent No. 331,646, dated December 1, 1885.

Application filed July 24, 1885. Serial No. 173,545. (No model.)

To all whom it may concern:

Be it known that I, ABRAHAM MILLER, a citizen of the United States, residing at Newark, in the county of Licking and State of Ohio, have invented certain new and useful Improvements in Clover-Hullers, of which the following is a specification, reference being had therein to the accompanying drawings.

This invention relates to clover-hullers; and the novelty consists in the construction, arrangement, and adaptation of parts for specific purposes, as will be more fully herein-after set forth, and specifically pointed out in the claims. It is designed as an improvement upon that class of machines similar to those patented to myself, No. 188,064, of March 6, 1877, and to Jones and Miller, No. 44,431, September 27, 1864. It relates more particularly to the lower cylinder and concave.

In the accompanying drawings, which form a part of this specification, Figure 1 is a section taken along the longitude of the machine. Fig. 2 is a similar view with the tool-box displaced. Fig. 3 is a face view of the lower concave. Fig. 4 is a detail view showing the peculiar means for detachably locking the tool-box in place. Fig. 5 is a detail section of one of the concave heads, and Figs. 6 and 7 are sectional views on the lines $y-y$ and $z-z$, respectively, of Fig. 5.

Referring to the drawings, A designates the frame of a clover-huller of the class described, and a the rear, and a' the front, thereof.

B designates one of the heads of the concave, having its outer flange, b , cut away, as seen at b' . The inner flanges, b^2 , serve as abutments for the staves, and the heads are beveled outward from the inner flanges to permit the easy removal of staves from the heads.

C designates the upper staves, which are held in place by the segmental flanges b and b^2 . C' are the lower similar staves, and C² the staves of the removable section. The lower of the staves C and the upper of the staves C' have peculiar features, and I will designate them by the marks C³ and C⁴ respectively.

D represents cleats or plates having handles d and end lugs, d' . To these cleats D, of which there are preferably two, are bolted or other-

wise secured the staves C³, which form the rigid detachable panel. The lugs d' operate under recesses e , formed in the lower surfaces of turning buttons E, arranged near the ends of the staves C³ and C⁴, for the purpose of holding the panel in position. If desired, the lower set of buttons may be rigidly secured to the staves C³, the upper set only having sliding motion. When this panel is removed, the staves C C' C³ C⁴ may be passed bodily through the opening thus made and pushed under the flanges b into their proper places, their location and arrangement being readily fixed to have the stationary and movable rubbers agree. The stave C³ has a longitudinal groove, through which the tie-rod c passes, and this tie-rod passing through holes or slots b^4 in the heads, in addition to the inner and outer flanges, holds this stave properly in place. I can use a joint bolt or screw at each end of this stave C³ in place of the tie-rod, but I prefer the rod. The upper and lower staves being properly located, there is left in the curve of the concave a space equal to the area of the movable panel formed by the staves C³, and this panel being put in place is securely locked by the buttons E to staves C³ and C⁴. By this construction not only are the staves readily and quickly put in proper place with regard to the proper juxtaposition, when in action, of the stationary and movable rubbers, but in case of the breaking of any of the rubbers, or for any other cause, the cylinder is readily accessible. In order to have ready access to the concave thus formed, I provide an open space in the rear of the machine, which is closed by the removable tool-box G when said tool-box is in the position shown in Fig. 1.

Secured to the end posts, a' , or to a board which may be secured to such posts, are locking-lugs F. The back part of the tool-box is perforated to receive these lugs, and to the inner surface of the tool-box are secured pivoted plates H, having guide-slots h which receive the bolts h' , and open slots h^2 , which receive and engage the lugs F, a thumb-screw, h^3 , serving to secure plates H in a locked position.

The slots h and open slots h^2 are formed with a curve describing the arc of a circle having 100

the pivot for a center, and the tool-box may be readily removed by the obvious manipulation of these parts to afford access to the concave. These features of construction are of 5 importance in this class of machines when inspection or repair of the working parts is necessary.

In details of construction modifications may be made within wide limits without departing 10 from the principle or sacrificing the advantages of my invention, the essential features of which will be readily understood from the foregoing description, taken in connection with the drawings.

15 What I claim as new is—

1. In a clover-huller, the concave heads having a portion of their outer flanges cut away to allow the insertion of the upper and lower staves, combined with a removable panel 20 having staves corresponding to such cut-away portion, as set forth.

2. The heads B, having inner flanges, b^2 , and outer flanges, b , cut away at b' , the said sides being beveled from the flange b^2 outward beyond the cut-away portion, as set forth.

3. In a concave of a clover-huller, the heads B, having slots b^4 , combined with a stave, C³, having a longitudinal slot and a tie-rod, e, a removable panel, and one or more separately-30 removable staves, as and for the purpose specified.

4. In a clover-huller, a concave consisting of upper and lower staves, two or more staves formed into a separate removable panel, and 35 means for securing the said removable panel in place, as set forth.

5. In a clover-huller, the combination of upper and lower staves with two or more staves formed into a panel, plates D, having projections d' , and buttons, as E, having recesses e, 40 as set forth.

6. In a clover-huller, the combination, with the upper and lower staves of the concave, of a removable panel consisting of a number of 45 staves, metal plates secured to said staves and

having handles, and buttons, as E, for locking said panel in place, as specified.

7. In a lower concave, the combination of the heads or sides B with cut-away flanges, the staves C³ C⁴, locking tie-rod e, removable 50 panel and sliding buttons arranged on said staves C³ C⁴ for locking said panel in place, as set forth.

8. The concave described, comprising heads or sides B, with cut-away flanges b b' , the 55 staves C³ C⁴, held by the flanges b b' , the removable panel formed by the staves C³, and plates D, with lugs d' , and the buttons E, with recesses e, as set forth.

9. The combination, with the lower cylinder and concave and the casing of a clover-huller having an open space opposite such concave, of a removable tool-box adapted, when in position, to cover said space, as set forth.

10. The combination, with the frame having lugs or pins, as F, of a removable tool-box, G, having slotted plates H, as set forth.

11. The combination, with the removable tool-box G and lugs F, of pivoted plates H, 7c having curved slots h^2 , and set-bolts h^3 , as and for the purpose set forth.

12. In a clover-huller, the combination, with the upper and lower staves of the concave, of a removable panel, plates secured to said panel 75 and having handles, and means for securing said removable panel in place, as and for the purpose set forth.

13. In a clover-huller, the combination, with two or more separately-removable staves, of a removable panel formed of two or more staves rigidly secured together, and means for securing said removable panel in place, as set forth.

In testimony whereof I affix my signature in 85 presence of two witnesses.

ABRAHAM MILLER.
